UNITED STATES PATENT OFFICE.

ADOLPH M. HOLSTEIN, OF SYRACUSE, NEW YORK.

DESIGN FOR A MANUFACTURED FIGURE FOR FURNITURE AND CASKET DECORATIONS
AND FOR INTERIOR AND EXTERIOR DECORATIONS.

52,077.

Specification for Design.

Patented June 4, 1918.

Application filed August 22, 1917. Serial No. 187,565. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for Manufactured Figure for Furniture and Casket Decorations and for Interior and Exterior Decorations, of which the following is a specification, reference being had to the accompanying drawing, forming a part hereof.

The drawing is an elevation of my new and ornamental design.

This design comprehends the representation of an elongated or tall basket filled with flowers, leaves, buds and twigs overflowing the top of the basket and arranged in symmetrical fashion and including twigs drooping at opposite sides of the basket to a point below the central part of the basket, the basket having a standing handle or bail

simulating a rope, and the body of the basket having the general appearance of an elongated inverted truncated cone or trumpet with concave or flaring sides, the lower base portion of which approximates a cylinder and the upper portion of which flares. The base portion is encircled by bands at the bottom and top of the merely cylindrical portion and the flaring top portion is provided with lengthwise corrugations, ridges or flutes.

I claim:

The ornamental design for a manufactured figure for furniture and casket decorations and for interior and exterior decorations, substantially as shown and described.

In testimony whereof, I have hereunto signed my name, at Syracuse, in the county of Onondaga, and State of New York, this 30th day of July, 1917.

ADOLPH M. HOLSTEIN.
